By J. Fraser, Esq.,
Atty.

United States Patent Office.

WILLIAM STREETER, OF ROCHESTER, NEW YORK.

Letters Patent No. 105,383, dated July 12, 1870.

IMPROVEMENT IN PERMUTATION LOCKS.

The Schedule referred to in these Letters Patent and making part of the same

To all whom it may concern:

Be it known that I, WILLIAM STREETER, of the city of Rochester, in the county of Monroe and State of New York, have invented a certain new and useful Improvement in Permutation Locks, of which the following is a specification.

Nature of the Invention.

My invention consists in the combination of spring pins, or equivalents, with the indented surfaces of washers or intermediate stationary bodies between the tumblers or wheels.

General Description.

In the drawing—

Figure 1 is an axial section.

Figure 2, a view of one of the washers removed from place.

Figure 3, a view of one of the pins separate.

Figure 4, an end view of the spindle with the spring collar applied.

Figure 5, a diagram, showing the friction device between the wheels and washers.

A is the spindle;

B B B, the tumblers or wheels; and

C O C, the washers between the wheels.

These parts are all arranged in the usual way.

Each wheel is bored with one or more holes, a, in which fits one or more pins, D.

These pins have a rounded point, b, which projects out from the face of the wheel; also, a shoulder, c, held in the hole by heading down the surface of the metal around it, by a punch or otherwise; and, furthermore, a shank, d, which extends down into the body of the hole, and is surrounded by a coiled spring, f, that forces the pin out.

Any different form of the pin may be used, and the spring may be differently arranged, or the pin and spring may be combined in one.

The washers C are of the usual form, but they are provided on one or both sides with a series of holes, notches, or indentations, k, which are coincident in position with the pins projecting from the faces of the two adjacent wheels.

The action is as follows:

When the spindle is turned the tumblers or wheels will be revolved in the usual manner, but, instead of the loose and irregular movement, such as is produced in ordinary locks, said wheels will act under a resistance which always keeps them in proper place. As they turn, the pins not only bear against the surface of the washers, but also strike into the indentations, and prevent the possibility of any slipping.

Much difficulty has been heretofore experienced from the loose action of the wheels, not only rendering it difficult to keep them in place while turning, but even after being set they can be jarred to different positions by any unusual movement.

The pins striking into the indentations will prevent any jar from displacing them under any circumstances when locked.

I disclaim the use of springs between the wheels, and also when applied to the peripheries of corrugated wheels; but

What I claim, and desire to secure by Letters Patent, is—

The combination of the spring pins D, or equivalent, with the indented surface of the washers or other intermediate stationary bodies between the wheels, as described.

In witness whereof I have hereunto signed my name in the presence of two subscribing witnesses.

WILLIAM STREETER.
